UNITED STATES PATENT OFFICE

THOMAS D. CASSERLY, OF CHICAGO, ILLINOIS, ASSIGNOR TO WEIL-MCLAIN COMPANY, OF MICHIGAN CITY, INDIANA, A CORPORATION OF DELAWARE

HEATER

Application filed April 9, 1928. Serial No. 268,515.

This invention relates to improvements in heaters.

As well known to those skilled in the art, there are many thousands of domestic boilers now in use, which were originally designed primarily for the burning of coal as a fuel, many of them for soft coal. Boilers so designed necessarily require a relatively large amount of flue area and correspondingly 10 large flue openings or passages to provide the necessary communication between sections where the boiler is of the water section type. Where coal is used as a fuel, there is a comparatively large volume of volatiles dis- 15 tillied off and also a relatively large volume of products of combustion, and these must be accommodated in the passage through the boiler or heater to the chimney, in order that as many of the heat units may be extracted 20 therefrom and transferred to the water sections as possible. It is also well known that a large number of said boilers now in use are annually being converted to use with gas as the fuel, and experience has demonstrated 25 that when so converted, the efficiency of the boiler is not as great as desirable. This is due to the fact that the volume of the products of combustion from gas as a fuel is relatively much less than the volume of the prod- 30 ucts of combustion of coal as a fuel for heating a given sized boiler, so that with gas as the fuel the lesser volume of products of combustion passes more rapidly through the flues and flue openings to the chimney and there is 35 not sufficient time allowed for properly extracting the maximum number of heat units therefrom.

One object of my invention is to provide 40 very simple and inexpensive means, in the nature of an auxiliary or accessory, that may be used with boilers now in use or new boilers originally designed for burning coal as the fuel, whereby the efficiency of such boilers, when using gas as the fuel, may be increased.

45 More specifically, an object of my invention is to provide baffle plates for restricting the area of the flue openings or communicating passages through the sections so that the effective available area of said openings will 50 be regulated to produce the most efficient op-

eration of the boiler when converted to use with gas as a fuel, said baffles or plates being further characterized by the fact that they may be readily inserted and put in proper position through the usual flue cleanout doors 55 of coal-burning boilers.

A further specific object of my invention is to provide removable baffles particularly designed for use with those types of sectional boilers where the flue openings of the horizontal water sections are staggered and alter- 60 nated on diametrically opposite sides of the centers of the sections, said baffles being so designed that when in proper position a balanced draft action is obtained. 65

In the drawing, forming a part of this specification, Figure 1 is a vertical, diametrical, sectional view of a round, horizontal, sectional type water heater or boiler, showing my improvements in connection therewith. Figure 2 is a horizontal plan view of one of the water sections showing my im- 70 provements in connection therewith, one of the flue cleanout doors being indicated in section. And Figure 3 is a top plan view of 75 one form of gas burner adapted to be em- ployed and showing also my improved means for restricting air in-flow.

In said drawing, 10 denotes the supporting base section of a round type boiler; 11 a water-containing fire-pot section; 12 a water-containing horizontal crown section; 13 a horizontal water-containing intermediate section; 14 a horizontal water-containing dome section; and 15 is a smoke-hood or take-off. The various water sections are in direct communication with each other by sets of nipples, two of which are indicated at 16—16 in Fig. 2, the same being located diametrically, as shown. The fire-pot section is provided with a clinker door 17, fuel door 18 and grates 19, of the usual type for coal-burning. The ash pit door is indicated at 21 and the horizontal water sections are provided with flue cleanout doors 22—22 arranged diamet- 85 rically in the usual manner. 90

The particular boiler illustrated is of the round type, as indicated in Figure 2, and each of the crown and intermediate sections is pro- 95 vided with an arcuate flue opening or pas- 100

sage 23. These flue openings 23 will be alternated or staggered, i. e., the flue opening 23 of the crown section will be at one side of the boiler, preferably at the back, and the flue opening 23 of the next above intermediate section will be at the opposite side of the boiler or at the front, as shown in Figure 1. Horizontal flues are left between the several sections, as indicated at 24—24, and the dome section has a passage 25 communicating with the smoke-hood 15, said passage 25 being staggered or alternated with respect to the flue opening 23 of the next lower section. Preferably, the sections are of that type having horizontal corrugations on the under sides thereof, as indicated at 261—261. As will be evident from the preceding description, considered in connection with the drawing, the products of combustion pass upwardly through the first flue opening 23, thence horizontally to the opposite side of the boiler, thence upwardly through the next flue opening 23, and so on until the products of combustion pass to the chimney, it being understood that there may be one or more intermediate sections 13, depending upon the desired capacity of the boiler.

The sizes of the flue openings 23 are shown in the drawing proportionate to the sizes of the sections as they would be made in the boiler designed for coal as the fuel. Where gas is used as the fuel, the area of the flue openings 23 is too great and allows the products of combustion of the gas fuel to pass too quickly to the chimney and only a small portion of the heat units is extracted. To overcome this, I provide the improved baffle plates 26, one of which is shown in top plan in Figure 2. Each baffle plate 26 is also of arcuate formation similar to the arcuate formation of the flue opening 23, but of lesser area than the opening 23, as shown in Figure 2. The length of each baffle plate 26 is such that the ends 126 thereof will extend slightly beyond the ends of the flue opening 23 and rest upon the top of the corresponding water section. The plates 26 are further made so that they preferably cover the inner portions of the arcuate openings 23, that is, those portions nearest the center of the boiler, the inner edge 127 of the plate slightly overlying the inner edge 123 of the flue opening. From the outer arcuate edge 128 of the plate is extended a radial flange 28 at the center, said flange 28 resting upon the water section beyond the outer edge 223 of the flue opening. Preferably, also, the flange 28 is formed with a depending lug or projection 29, adapted to engage the vertical wall 223 of the flue opening and hence limit or position the baffle plate 26 to that shown in the drawing.

With the baffle plates positioned as shown and described, it is evident that the area of the flue openings 23 is materially reduced and the effective flue opening consists of a

relatively narrow arcuate opening farthest from the center. The flue openings of the section being staggered and diametrically disposed, the tendency for the products of combustion is to take the shortest route to the chimney, that is, to pass back and forth on a diametrical line. By forming the flue openings 23 of elongated arcuate form and making the baffle plates 26 of corresponding shape, the products of combustion are induced to spread over the entire areas of the water sections. The distance between the end portion of one flue opening 23 and the nearest end portion of the flue opening 23 in the adjacent section is less than the distance between the central points of such two flue openings and hence the greater draft at the central portions, which induces the back and forth travel of the gases, will be compensated for by the lesser amount of travel required for the gases between the end portions of the flue openings. In this manner, a more uniform distribution of the products of combustion over the horizontal surfaces of the sections in the travel back and forth through the boiler is obtained, and the use of my specially shaped baffle plates 26 serves to maintain this condition when the boiler is converted to use with gas as the fuel.

Referring to Figure 2, it will be seen that the baffle plates 26 are of such size and shape that the same may be readily entered and removed through the cleanout door 22, which is located closely adjacent the corresponding flue opening 23, with which the baffle plate is adapted to be associated. In this manner, the size of the flue openings may be readily changed without taking down the boiler sections when it is desired to convert the boiler for burning gas.

As will be appreciated by those skilled in the art, any desirable type of gas burner may be employed. In the drawings, I have illustrated one well known form, the same consisting of a central unit 40 and three outer units or gangs 41—41 which unit or gang consists of a plurality of gas burners or tips 42 proper, preferably arranged as best illustrated in Figure 1, so that two burners or tips are disposed adjacent each other and the jets therefrom will mingle and form a common flame for each pair. The gas is supplied to the gang or burners by suitable piping as indicated at 43. The gas burners per se form no part of my invention, but the same are shown employed in connection with a plate 44 of circular form, the plate resting upon the grate bars 19 and being of such area as to shut off, for all practical purposes, passage of air from the ash pit 45 to the combustion chamber of the fire-pot. Said plate 44 is preferably made in two semi-circular sections. The plate 44 is provided to restrict the in-flow of air from the ash pit of the combustion chamber and hence to the gas burners, since an

unrestricted flow would result in inefficient heating of the boiler. The flow of air is regulated by providing a series of spaced holes or openings 47—47 arranged preferably in a circular series around the plate 44, the area of the individual openings 47 being relatively small and the openings being uniformly spaced so as to thereby admit of a plurality of small currents of air at uniformly spaced 10 points adjacent the periphery of the fire-pot and directly beneath the gas jets. By making the plate 44 in two sections, it is evident that the same may be readily inserted through the fuel feed door without dismantling the heater.

15 I have herein shown and described what I now consider the preferred manner of carrying out my invention, but the same is merely illustrative and I contemplate all changes and modifications that come within the scope 20 of the claim appended hereto.

I claim:

In a boiler, the combination with horizontal water-containing sections having horizontal flues therebetween and provided with 25 cleanout doors, said sections being provided with flue openings alternately disposed on diametrically opposite sides of the boiler, each flue opening being of arcuate formation concentric with the center of the boiler; and 30 detachable baffle plates, insertable through the cleanout doors for said flue openings, each said plate being also of arcuate formation and arranged to cover the innermost side of each arcuate flue opening whereby to leave 35 relatively narrowed flue openings at the maximum distance from the centers of the sections and thereby insure more uniform distribution of the products of combustion back and forth between the sections.

40 In witness that I claim the foregoing I have hereunto subscribed my name this 24th day of March, 1928.

THOMAS D. CASSERLY.
